Baldwin & Wright

UNITED STATES PATENT OFFICE.

EMIL GATHMANN, OF BALTIMORE, MARYLAND.

INGOT MOLD.

Application filed November 29, 1927. Serial No. 236,494.

This invention relates to metallic ingot molds open at top and bottom, and particularly to molds of the kind commonly used for casting steel ingots. Molds of this kind are commonly mounted on a "stool" or similar support which in many cases has a projection which enters the bottom opening of the mold and assists in stripping or detaching the ingot from the walls of the mold chamber, while in other cases the stool or supporting plate is formed with an opening which registers with the bottom opening of the mold and through which a stripping plug may be inserted and operated to detach the ingot from the mold walls. My present invention relates particularly to this last-mentioned kind of molds.

In the case of all molds supported on a stool or supporting plate, there is danger of the molten steel passing laterally out of the mold chamber into or through the joint between the bottom of the mold and the top of the stool, and thus forming "fins" which prevent or impede the free stripping of the ingot from the mold. Various devices have been used to prevent the formation of such fins and several patents have been issued to me for this purpose as shown, for instance, in the following U. S. patents: No. 1,019,244, No. 1,170,629, No. 1,188,751, No. 1,209,283, No. 1,570,473, No. 1,611,020, No. 1,630,612, No. 1,643,241, No. 1,649,522.

It is also important that the lower portion of the mold chamber and the walls of the bottom opening should be so formed that the ingot may be easily stripped from the mold and that said walls shall be protected against the effects of the impact and erosive action of the liquid steel while being teemed into the mold.

In my U. S. patents, for instance, No. 1,170,629, No. 1,188,751, No. 1,611,020, and No. 1,643,241, I have shown different ways of forming the mold chamber and the bottom opening of the ingot to facilitate stripping of the mold and for preventing or reducing the injurious effect often caused by the action of the steel while being poured.

My present invention relates particularly to the means employed for closing the bottom opening of the mold, for protecting the mold walls and for stripping the ingot from the mold.

According to my invention the opening in

the bottom of the mold is closed by a plug which enters the bottom opening and preferably rests on a ledge formed by the stool and surrounding an opening therein, which is concentric with the bottom opening of the mold. The stool has an opening passing through it in which a stripping plug is arranged which may be raised so as to come in contact with the bottom of the sealing plug and support it, and thus sustain the weight of metal in the mold during the pouring and casting operation. In this way the strain on the sealing plug is largely relieved. The opening in the stool may be of two diameters so that a ledge or shoulder is formed on the upper portion of the stool on which the sealing plug rests either when idle or while the mold is being poured. The sealing plug may be cup-shaped or solid. It is preferably formed cup-shaped of relatively thin metal made strong enough to seal the mold opening and to support the metal during the pouring of the mold and until the mold is stripped, when it passes out of the mold with the ingot to which it adheres.

Other features of my invention and the details of construction will be hereinafter more fully described.

In the accompanying drawings:

Figure 1 shows a vertical central section through a portion of an ingot mold and a portion of a stool on which the mold is supported. Parts of the mold are broken away for convenience of illustration.

Figure 2 is a horizontal section on the line 2-2 of Figure 1.

Figure 3 is a perspective view of a hollow cup-shaped sealing plug which may be employed.

Figure 4 is a detail view of the sealing plug.

Figure 5 is a sectional view, showing a modification.

Referring to the first four figures of the drawings, a portion of a Gathmann ingot mold is illustrated in which the walls A of the mold are made thicker and thus more heat absorptive in the lower portion of the mold than in the upper portion thereof. The purpose of this construction is now well understood in the art. The lower portion of the mold chamber is necked-in in the manner illustrated for purposes explained in

some of my prior patents above mentioned. The mold is provided with a bottom opening B which tapers, as indicated, from its upper end downwardly, joining at α the necked-in portion of the lower part of the mold cavity. This bottom opening may, for some purposes, be considered as a part of the mold cavity as it would be if it were not occupied by a sealing plug, and where 10 a hollow sealing plug is used, as shown in Figure 1, the molten metal fills the plug and the hollow or cavity in the plug is thus made a part of the mold chamber. It will be observed that the mold walls are rounded at α where the walls of the bottom opening join the straight or flat walls α' which latter merge into the curved walls α^2 .

In order to seal the bottom opening while the molten metal is being poured into the 20 mold to prevent leakage, I may employ a hollow sealing plug of the kind illustrated in Figures 1, 2, 3 and 4. The exterior walls of this plug are tapered to fit the walls of the bottom opening of the mold. They fit 25 it very closely so that molten metal cannot pass all the way downwardly between the walls of the plug and the walls of the bottom opening and there is thus no chance of an escape of molten metal from the bottom 30 of the mold.

In the form of my invention illustrated in Figure 1, the mold rests on a stool C provided with a stripper or stripping plug D which is movable vertically in the stool. 35 It is possible to support the mold on a solid stool and to move the mold, when ready for stripping, to a truck, for instance, provided with a projection adapted to contact with the sealing plug, and raise the ingot so as 40 to detach it from the walls of the mold, and permit of its removal therefrom by means of lifting/tongs or grippers of some kind. However, I prefer to retain the mold on the stool and to form the stool with an opening 45 through which a stripping plug may be passed without moving the mold. This stripping plug may be carried by a truck and may be raised at the proper time into contact with the sealing plug in order to 50 raise the ingot sufficiently to separate it from the mold walls, but I prefer to mount the stripper in the stool so that it is separable therefrom but is supported thereby. As indicated in Figure 1, the stripper may have 55 an enlarged upper portion d and a lower portion d' which extends below the bottom of the stool. The enlarged upper portion d may rest on a ledge α' formed around the opening through which the stripper D 60 passes.

When the stream of molten metal is teemed into the mold it should be so directed that the hollow sealing plug E will receive the impact and erosive action of the metal and 65 any initial splashing will be largely confined

to this plug. The necked-in walls of the mold cavity will thus be relieved from much injury which would otherwise be likely to occur. When the mold is partially filled with molten metal, the stripping plug D 70 may be raised to come in contact with the bottom of the sealing plug so as to sustain the weight of metal in the mold and to partially take the strain from the sealing plug. After the metal is solidified and the ingot 75 is formed the stripper may be moved so as to push on the sealing plug and raise the ingot sufficiently to loosen them from contact with the walls of the bottom opening and the walls of the mold so that the ingot may 80 be readily removed from the mold by lifting tongs or other such devices.

In Figure 5 I have shown a modification in which the sealing plug is made solid and is supported on the shoulder α of the stool carrying the mold while in contact with the plug D. While I prefer to use a hollow sealing plug it should be understood that I 85 may use a solid plug E' adapted to rest upon a ledge of a stool as illustrated. 90

I claim as my invention:

1. An ingot mold open at the top and having a bottom opening, in combination with a stool having an opening through it of smaller diameter than the bottom opening of the mold, and a sealing plug resting on the ledge or shoulder thus provided on the stool surrounding this opening. 95

2. An ingot mold open at the top and having a bottom opening and a sealing plug, in combination with a stool having an opening through it of smaller diameter than the bottom opening of the mold, and a stripping plug extending into the opening of the stool and adapted to support and to raise the 105 ingot from the mold.

3. An ingot mold open at the top and having a bottom opening, in combination with a stool having an opening through it of smaller diameter than the bottom opening of the mold and having a shoulder between its upper and lower ends, a sealing plug filling the bottom opening of the mold, and a stripper having its upper portion resting on the shoulder formed in the stool and having its lower portion extending beyond the bottom 110 of the stool. 115

4. An ingot mold open at the top having a necked-in lower portion, and a bottom opening the walls of which merge into the necked-in portion of the mold, a sealing plug filling the bottom opening extending from the top of said bottom opening to the bottom thereof, a stool having an opening extending through it, and a stripping plug arranged in said opening adapted to move vertically therein into contact with the sealing plug and to raise said sealing plug with the ingot when formed. 125

5. An ingot mold open at the top and 130

having a bottom opening, in combination with a stool having an opening through it of smaller diameter than the bottom opening of the mold and provided with a ledge or shoulder between its upper and lower ends, a sealing plug extending from top to bottom of the bottom opening in the mold, and a stripping plug having an enlarged upper end resting on the shoulder of the opening in the stool and having a lower portion 10 extending below the bottom of the stool. In testimony whereof, I have hereunto subscribed my name.

EMIL GATHMANN.
